UNITED STATES PATENT OFFICE.

CHARLES C. SPREEN, OF DETROIT, MICHIGAN, ASSIGNOR, BY MESNE ASSIGNMENTS, TO KELVINATOR CORPORATION, OF DETROIT, MICHIGAN, A CORPORATION OF MICHIGAN.

REFRIGERATING APPARATUS.

Application filed October 31, 1924. Serial No. 747,022.

To all whom it may concern:

Be it known that I, CHARLES C. SPREEN, a citizen of the United States of America, and a resident of Detroit, in the county of 5 Wayne and State of Michigan, have invented certain new and useful Improvements in Refrigerating Apparatus, of which the following is a full, clear, and exact description.

This invention relates to refrigerating 10 apparatus especially of the type employed for domestic purposes and has for its object the provision of a new and improved brine tank construction which shall facilitate the assembling of the brine tank and 15 safe-guard the internal parts thereof against injury during transportation. Further objects of the invention will become apparent as the description proceeds.

In the drawings accompanying and forming 20 a part of this application I have shown certain physical forms in which my inventive idea can be embodied although it will be understood that I do not limit myself to the forms or constructions shown herein 25 except as the same are specifically recited in my claims.

Figs. 1 and 2 are sectional views at right angles to each other of a typical brine tank as employed for mechanical refrigeration; 30 Fig. 3 is a plan view of one of the spacing bars shown in Fig. 1; Fig. 4 is an enlarged detail view showing one of said spacing bars in place; and Fig. 5 is a view similar to Fig. 4 showing a modified form 35 of spacing bar.

In mechanism of this character it is customary to employ a rectangular sheet metal tank 1 filled with brine, alcohol solution, or other low freezing point substance which, 40 when thoroughly cooled, may serve to maintain the food compartment at the desired temperature for a considerable period without running the motor. Submerged in this brine are suitable turns of pipe constituting 45 a coil for the expansion of the refrigerant, these coils being frequently looped about suitable chambers or flues adapted for the reception of meat, ices, trays of water, or other substances desired to be chilled or 50 frozen. In the present embodiment I have illustrated three horizontal flues 2, 3, and 4 traversing the tank from front to back, the several flues being surrounded each by a horizontal coil of piping, 5, 6, 7, respectively, which together constitute the ex-

pansion chamber and terminate in fittings 8 and 9 at the top of the tank. I have shown the flue 4 as formed of a height to take only a single tray of water, flue 3 is of the height to take two trays and flue 2 of a height to take three trays. When plural trays are employed in a single flue, the upper trays are supported by having their flanges slid upon suitable rails or shelves 15, 15; but the number or size of the flues or the number of trays they contain are not important to the present invention.

In the practical manufacture of devices of this character it is necessary to form the 70 coils on mandrels; to erect and solder the tank independent of the coils; to paint or lacquer the soldered seams of the tank interior prior to the introduction of the coils, in order to increase the life of the tank; 75 then to introduce the coils into the tank from above; then to introduce the flues transversely into the coils; and finally to solder the flues in place and the tank top to walls. This necessity of inserting the flues into 80 the tank at the last necessitates making the coils sufficiently large to prevent binding, yet the considerable axial length of the coils causes them to sag and enables destructive vibration. Both the tank and the 85 coils are necessarily made of soft metals, since only these have the requisite resistivity to the corrosive effect of the refrigerant and brine, pure copper being the preferred substance, and the same are necessarily made 90 rather thin, both to minimize weight and to facilitate heat exchange. As a result experience has shown that a considerable percentage of all brine tanks shipped more than one thousand miles have actually had 95 holes worn either in the coils or in the flues by the vibration.

In order to overcome this difficulty I interpose between each corner of each flue and the corresponding bend of the coil a 100 suitable bracing strip 10 which shall both facilitate the assembling of the device and prevent vibration and wear during transportation. In its preferred form this strip is made of wood of the appearance shown in Figs. 3 and 4, one face being grooved to engage the corner of the flue and the opposite face being rounded to conform with the bend of the pipe; although other substances can be used such as the metal 105 110

strip 10^a as shown in Fig. 5 wherein the edges 11, 11 are rolled to engage the flue, thus distributing the wear. Inasmuch as it is impossible to introduce the hand into the interior of the tank after the coils are inserted therein, means are provided to secure these strips to the respective coils prior to their introduction. These means preferably comprise wire staples 12, 12 adapted to straddle one or more turns of the coil, the legs of the staple being passed through spaced holes 13, 13 formed in the strips, and the grooved face of the strip being recessed between these holes as shown at 14 to receive the body of the staple and displace the same out of the path of the flues.

In case of the metal strip shown in Fig. 5 the hollow interior of the strip dispenses with the need of any special provision for this staple. It is necessary to give the legs of these staples only a partial turn sufficient to hold the strips in a position to receive the flues.

After the tanks are set up and filled with brine it makes little difference what happens to these strips, inasmuch as transportation thereafter is of very rare occurrence. When made of wood these strips disintegrate more or less rapidly yet this is of minor importance and so far as life is concerned the strips might equally well be made of paper board or similar substances.

Having thus described my invention what I claim is:

1. In refrigerating apparatus, a brine tank comprising a horizontal metal flue,

an expansion coil bent into a coil surrounding said flue, in combination with a plurality of horizontal spacing strips interposed between said coil and the walls of said flue, and means securing said strips to said coil.

2. In refrigerating apparatus, a brine tank having therein a chamber which opens through one or more walls thereof, an expansion coil comprising a coil of pipe embracing said chamber, and a plurality of spacing strips interposed between said coil and the walls of said chamber and adapted to prevent mutual wear of said pipe and walls during transportation.

3. In refrigerating apparatus, the combination with the expansion coil, of a plurality of spacing strips carried by the inner surface thereby and comprising elongated members adapted to engage the walls of a freezing flue, said strips having pairs of apertures adapted for the reception of securing staples, there being recesses between the holes of each pair.

4. In refrigerating apparatus in combination a brine tank having holes in its walls and rectangular sheet metal flues secured in said holes and constituting horizontal freezing chambers, coils of pipe operatively associated with each of said flues, spacing strips interposed between each coil and the adjacent flue, and means securing each end of each strip to said coils.

In testimony whereof, I hereunto affix my signature.

CHARLES C. SPREEN.
